A. R. HOEFT

TRAP NEST DOOR FOR POULTRY

Filed April 11, 1924

UNITED STATES PATENT OFFICE.

ADOLPH R. HOEFT, OF CHICAGO, ILLINOIS.

TRAP-NEST DOOR FOR POULTRY.

Application filed April 11, 1924. Serial No. 705,831.

This invention relates to improvements in trap nests for laying fowls, and refers more particularly to an improved trap nest front which includes a novel door that is adapted to be set for the entrance of the fowl into the nest, the setting means being tripped by the fowl when entering the nest to close the front opening of the nest until the door or closure is raised to release the fowl.

10 Among the objects of the invention is to provide a door structure of this character in which closure sections, having swinging and relatively sliding movement, are so arranged that the closure elements will be locked from swinging inwardly when disposed in one position of their sliding movement, and, in another position, will be left free to be swung inwardly and upwardly either to set the closure for the entrance of a fowl or to open the closure to remove a fowl.

Another object of the invention is to provide a closure of this character which can be set for fowls of different heights. In the use of the present invention, the closure elements are adapted to be set in position to afford space for a fowl to pass therebeneath but at such height that the back or tail of the fowl will release the setting means and permit the closure sections to fall by gravity into closing position; there to be held until the closure sections are manually operated to open the closure.

Another object of the invention is to provide a closure of this character which is included in and made part of a larger door which is adapted to be hinged to the front of the nest and locked in closed position whereby the entire front dimensions of the nest 40 may be opened for cleaning the nest.

Other objects are to further improve, simplify and reduce the cost of trap nest doors and the invention consists in the elements and combination of elements shown in the drawings and described in the specification, and pointed out in the appended claims.

In the drawings:

Figure 1 is a front view of a trap nest door embodying my invention.

50 Figure 2 is a section on the line 2—2 of

Figure 1, showing the door in closed position.

Figure 3 is a similar section showing the door in set position.

Figure 4 is a fragmentary detail section 55 showing the closure sections in partially raised position, on an enlarged scale.

Figure 5 is a fragmentary, inside view of the structure.

Figure 6 is a section on the line 6—6 of 60 Figure 5.

As shown in the drawings:

10 designates, as a whole, the nest which may be made of any desired form or material and it is here shown as provided with 65 a front wall 11 that is cut out to produce a front opening 12 over which my improved trap nest door is designed to be fitted.

The trap nest door herein shown embraces in general two elementary structures, to-wit: 70 a metal plate 14 which partially overlaps the front wall outwardly beyond the opening 12 and is centrally cut away to produce in itself an opening of substantially the same dimensions as the opening 12, and two closure elements 15, 16 that are arranged to close the opening in said plate 14 when disposed in given positions and when disposed in other positions to be moved away from and clear the opening in said plate 14. The plate 14 is provided at its inner margin with narrow 75 inturned centering flanges 17 to center the plate relatively to the front opening in the nest.

Said plate 14 constitutes in itself a door 85 that is mounted to swing about hinges 18 at the lower margin thereof to clear the full front opening, and is adapted to be locked in closed position by means of a rotative screw eye 19 that is screwed into the front 90 of the nest and is adapted, when turned transversely to a slot 20 at the top of the plate, to release said plate to allow it to swing downwardly; but when turned transversely to the slot to lock the door plate in 95 its closed position.

The closure sections 15, 16, as before stated, close the nest opening formed in the door plate 14. There are two of these closure sections, as shown. The closure sec- 100

tion 15 is hinged at its upper margin to the door plate 14 by a rod 21, the ends of which rod are fixedly mounted relatively to the door plate 14. As herein shown, said ends of the rod extend through and closely fit in openings in the inner flanges 22 of reinforcing channels, designated as a whole by 23; said channels being arranged in pairs, one at each side of the opening in the door plate and riveted thereto. The closure section 16 is slidable on the closure section 15 and the depth of both sections are such as to substantially close the opening in the door plate 14. The slidable connection of the closure section 16 to the closure section 15 embraces a rod 24 fixed to the upper margin of the closure section 16, extending across and inside the closure section 16, and is slidable at its end in slots 25 formed in the inner flanges 22 of the channel reinforcing bar 23, above referred to. Said slots 25 occupy the upper ends of said channels 22, as best shown in Figures 2 and 3. The lower part of the closure section 16 is confined relatively to the closure section 15 by means of lips 26 formed integral with the side margins of the closure section 15 and lapped backwardly over the rear face of the door closure section 16.

30 27 designates a latch bar which is hinged to the outer face of the upper closure section 15 and which is pivoted at its upper end on the outer face of said upper closure section 15 and is adapted for setting or interlocking engagement at its lower end with a plurality of notches 28 formed in the door plate 14 at one of its vertical members. Figure 1 shows the elements of the structure assembled and with the lower closure section occupying its extended position so that it and the upper closure section close the opening in the door plate 14. By reason of the fact that the hinges of the upper and lower closure sections are at this time spaced from each other, as indicated by the dotted line positions of the hinge rods 21 and 24, it will be noted that the two closure sections can not be swung inwardly about the upper hinge rod 21. Therefore, when the parts 40 are in the position shown in Figure 1, the fowl can not enter the nest. To open the nest for the entrance of a fowl, the lower sliding and swinging closure section 16 is moved or slid upwardly inside the upper closure section 15 by reason of the guiding engagement afforded by the lips 26 and the ends of the pivot rod 24 passing through the slots 25 until the pivot rods 21 and 24 are brought to a common swinging center for both closure sections. Thereupon, both closure sections are swung inwardly into the position illustrated in Figure 3 and are set in such position by engagement of the free end of the latch bar 27 by one of the notches 28. When the closure sections oc-

cupy the position shown in Figure 3, space is afforded between the backwardly inclined closure sections and the floor of the nest to permit a fowl to pass into the nest. The height of the free ends of the closure sections, however, can be varied by engaging the latch bar end with any one of the notches 28. In any event, it is assumed that the lower edges of the closure sections will be engaged by the back or the tail of the fowl to raise them such a distance as to permit the setting latch bar to drop down. After the fowl has passed the closure sections, the latter will, by gravity, swing outwardly toward the opening in the door plate 14, and the lower or slidable closure section will slide down and relatively to the upper closure section to completely close the front opening of the nest. As before stated, the closure sections cannot be again opened by a fowl attempting to enter the nest by reason of non-concentric relation of the hinge rod 24 to that of the rod 21, and the fowl in the nest can only be released by sliding the lower closure section upwardly to bring the pivots of the two closure sections into or near the plane of the axis of the hinge or pivot rod 21.

The lower closure section will be limited in its drop by engagement of its rod 24 with the bottom of the notches 25. The lower margin of said lower section, however, is cut away or curved upwardly to permit the hand to be inserted thereunder to raise said section preparatory to opening the nest front; and the position of the latch is such that said lower section may be raised and both sections swung backwardly and the latch bar 27 may be operated by one hand of a person who, with his other hand, can remove the fowl and an egg from the nest.

The closure sections will desirably be provided with ventilating openings, as shown in Figure 1, and may also be so disposed at their upper and lower margins relatively to the upper and lower margins of the main door opening so as to provide other ventilating openings to properly ventilate the nest.

In order to afford a further protection against rearwardly opening the door, comprising the sections 15 and 16, suitable stops may be set at the lower part of the door opening which will be engaged by the lower closure section when the door structure is closed. Said stops may be made of any suitable structure, as for instance the inner flanges of the channel bars 23 may be slotted to produce stop tongues 30, as shown in Figures 1, 2 and 3.

While the details of the embodiment shown have been described with considerable particularity, it will be understood that said details may be varied within the scope of the appended claims and that the inven-

tion is not limited to the illustrated embodiment thereof except as to claims wherein the particular details are specifically set forth.

I claim as my invention:

5 1. In a trap nest door, a swingable upper section having a fixed pivot, and a lower section interlocked with the first section so as at all times to be held in parallel relation thereto and slidable thereon, and pivot 10 means for said second section movable from and toward said fixed pivot.

2. In a trap nest door, a swingable upper section having a permanent pivot, a lower section held parallel with and slidable on 15 the first section and swingable about a pivot movable from and toward the other pivot, one of said sections having guide means engaged with the other to maintain the two sections at all times in parallel relation to 20 each other.

3. The combination with a door section mounted to swing on a fixed pivot, a part relatively stationary to said fixed pivot and having a slot extending from a point adjacent to the fixed pivot along the aforesaid section when the latter is closed, of a pivot element movable in said slotted part, a second section connected to said movable pivot, and interlocking means between said 30 sections to maintain them in parallel relation to each other.

4. A trap nest door comprising a door adapted to be hinged to the front of a nest and having means to lock it in closed position, said door being itself provided with an 35 opening, a closure for said opening comprising two sections, slidable one on the other, one of said sections being connected to a fixed pivot and the other to a pivot movable toward and from the fixed pivot, and trigger means to set the closure sections in inwardly swung-open position.

5. A trap nest door comprising a door adapted to be hinged to the front of a nest and having means to lock it in closed position, said door being itself provided with an 45 opening, a closure for said opening comprising two sections, slidable one on the other, one of said sections being connected to a fixed pivot and the other to a pivot movable toward and from the fixed pivot, and trigger means to set the closure sections in 50 inwardly swung open position, said section connected to said movable pivot being slidable by gravity on said other section upon tripping of said trigger.

6. In a trap door for fowl nests, two 55 swingable door closure sections lying flat against each other and connected to slide upon each other, one having pivoted connection to a stationary part and the other having a pivot that is slidable relatively to the first closure section pivot to bring said closure sections in overlapping relation to per-

mit both sections to swing about a substantially common pivot center. 65

7. The combination with a nest having a front opening, of two closure sections connected together to slide upon each other and adapted to close said opening when in non-overlapping relation, one of said sections being pivoted to a fixed part and the other having a pivot in sliding engagement with said fixed part, and a releasable setting trigger to hold said sections swung inwardly 70 toward the nest when disposed one in overlapping relation to each other.

8. The combination with a nest having a front opening, of two closure sections to close said opening, one slidably connected to the other, one of said sections being pivoted to a fixed part and the other having a pivot relatively slidable to said fixed part, and trigger means to hold the door sections 75 in open position when lying one over the other, both sections swinging downwardly by gravity and the slidable section moving on the other section by gravity when said trigger means is released. 80

9. The combination with a nest having an 85 opening, of a closure therefor, comprising upper and lower closure sections, the upper section being permanently hinged relatively to the nest and the lower section being swingably mounted on a pivot which is movable towards and from the hinge of the upper section, and fixed, slotted guide means to guide said pivot when the lower section is moving in a path parallel to the said upper section, the parts being so proportioned that when the lower section is raised to its upper limit, the two pivots are brought close together. 90

10. A door for a nest comprising a frame member having a central opening and hinged at its lower end to the nest and provided with means at its upper end to detachably lock it closed, slotted reinforcing members fixed to said frame member at the sides of its opening, and two closure sections lapping one over the other and interlocked so as to be held in parallel relation to each other, one permanently hinged to said reinforcing members and the other having a pivot slidable in the slots of said reinforcing members toward and from the hinge of the first closure section. 105

11. A trap door for a nest opening comprising a frame having a central door opening, reinforcing means on the inner side of said frame at the sides of said door opening, two door sections lapping one over the other and interlocked so as to be held in parallel relation to each other, one hinged to said reinforcing means and the other having a pivot slidable on said reinforcing means toward and from the hinge of the first section, and a latch pivoted to said first section 110

and adapted for separate, releasable engagement with vertically spaced notches on said frame.

12. A trap door for a nest opening comprising a frame, an upper door section and a lower door section adapted to close the opening in the frame, the upper section being hinged at its upper end to said frame, vertical guides on the frame in rear of and adjacent to said upper section, and there

being projections on the upper end of the lower door section engaged with said guides to permit the lower section to be raised bodily and also to be swung about a transverse axis near the top thereof.

In witness whereof I claim the foregoing as my invention, I hereunto append my signature this 8th day of April, 1924.

ADOLPH R. HOEFT.
